ELECTRON DISCHARGE DEVICES AND CIRCUIT
COMPONENT STACKED ASSEMBLY

Walter Grattidge, Schenectady, N.Y., assignor to General
Electric Company, a corporation of New York
Continuation of abandoned application Ser. No. 607,732,
Sept. 4, 1956. This application Mar. 22, 1962, Ser.
No. 181,689

4 Claims. (Cl. 315—59)

The present invention relates to an improved electric discharge device and circuit component assembly and more particularly to an improved stacked assembly of this type adapted for high temperature operation. This application is a continuation of my copending application Serial No. 607,732, filed September 4, 1956, (now abandoned) and assigned to the assignee of this application.

There have been developed a number of applications for electric discharge devices presenting stringent requirements with respect to one or more of the following: high ambient temperature, vibration or shock, premium on space, and the ability to operate in a region subject to nuclear radiation. The same requirements apply to circuit components which are necessarily associated with the electric discharge device so applied. In accordance with my invention, I provide a composite stacked structure providing one or more discharge devices and at least a substantial portion of the circuit components employed therewith. More specifically, passive circuit elements such as circuit resistances, for example the anode or plate resistance and the grid-cathode or input resistance, are formed on inner surfaces of insulating parts of an evacuated envelope in a manner which eliminates a number of circuit connections and substantial external wire. The assembly is characterized by a marked improvement as compared with the prior art with respect to each of the requirements mentioned above.

It is an object of my invention to provide a new and improved stacked assembly providing an electric discharge device and associated passive circuit components.

It is another object of my invention to provide a new and improved assembly providing an electric discharge device and one or more passive circuit components in an evacuated envelope which is compact, rugged and operable in high ambient temperatures. Further objects and advantages will become apparent as the following description proceeds, reference being had to the accompanying drawing and its scope will be pointed out in the appended claims.

In the drawing, FIG. 1 is an elevational view in section of an electric discharge device and circuit component assembly embodying my invention, FIG. 2 is a schematic wiring diagram of the circuit provided by the assembly of FIG. 1, FIG. 3 is an elevational view partially in section of a modified form of my invention, and FIG. 4 is a schematic wiring diagram of the circuit provided by the assembly of FIG. 4.

Referring to FIG. 1 of the drawing, I have shown my invention embodied in a stacked assembly providing a triode type of electric discharge device, together with the anode or plate resistor and grid-cathode resistor both formed within the device in such a manner that the circuit connections with the electrode are completed during manufacture of the device. The stacked assembly includes annular insulating members 10-13, inclusive, and conducting terminal members 14-18, inclusive, alternatively arranged and bonded together to provide five mutually insulated terminals spaced by the insulators and forming a vacuum-tight envelope. The ceramic insulators may be of any type suitable for use in electric discharge devices but are preferably alumina bodies or one of the newer fosterite bodies which have expansion characteristics com-

2

patible with those of titanium. The bodies are of high purity and give off very little gas even when raised to a temperature of several hundred degrees centigrade. The terminal members may be of any suitable conducting material and titanium or copper have been found particularly suitable.

Within the envelope, the various electrodes of the device are supported in spaced axial relation. The anode 19 may be formed integrally with the anode terminal 15, the grid 20 supported by a grid ring held between the upper surface of the insulator 12 and the grid terminal 16. The cathode 21, as shown, is in the form of an inverted cup-shaped member having the upper surface 22 thereof in closely spaced relation with the grid 20. The cathode member 21 is coated on the upper surface thereof with an electron emission enhancing material, such as one of the alkaline earth oxides in accordance with a practice well understood in the art and is heated to emissive temperature by means of a resistance heater 23 connected at one end to a central portion of the closed end of the cathode member 21 and at the other end to the heater terminal 18.

In accordance with an important feature of my invention, the inner wall of the insulator 12 surrounding the cathode 21 is provided with a coating 24 which provides a film resistor connecting the grid supporting ring and the cathode sleeve. In a similar manner, the insulator 10 is provided with a resistance coating 25 on its inner surface which extends between the conducting discs 14 and 15. These coatings are formed by applying to these surfaces a coating which is reduced during the firing and sealing of the envelope structure and its resistance is controlled by the nature of this coating and the processing applied thereto.

While the resistance coatings 24 and 25 may be made by a wide variety of methods depending upon the resistance characteristics desired, the grid cathode resistor 24 having a resistor from 1000 ohms to 100,000 ohms but preferably in the order of 10,000 ohms may be formed to advantage by the method described and claimed in Beggs Patent No. 3,013,328, granted December 19, 1961, entitled "Conducting Film." In accordance with one method there described, the surface of the ceramic on which the resistance film is to be formed, specifically the inner wall of the ceramic insulator 12, is painted with a mixture of approximately 30% iron and 70% titanium hydride by weight, in a binder including a carbonaceous compound such as nitrocellulose. One of the advantages of a coating of this type is that it may be formed in place during the exhaust and sealing of the stacked assembly, as will be described in more detail later in this specification. It will also be understood that other materials and percentages of the composition may be employed depending upon the magnitude of the resistance desired.

In many applications, it is desirable that the grid-cathode resistor be of substantially higher magnitude than readily obtainable by the method described above, and if a resistance in the order of .1 to 100 megohms, for example, is desired, the method described and claimed in Beggs and Grattidge Patent No. 2,961,352, granted November 22, 1960, may be employed. In accordance with one embodiment of the invention there described, the inner wall of the insulator 12 is coated with an oxide such as Fe_2O_3 , TiO_2 or ZrO_2 in a suitable organic binder such as zapon and the coated insulator fired. There also must be available during the processing of the coating a hydrogen-producing agent in order to reduce the oxide to a desired extent and in this way control the resistance of the film. This supply of hydrogen may be provided readily by the presence of titanium hydride, which is exposed to the interior of the device. Since a preferred manner of assembling the envelope of this stacked device includes the use of titanium hydride, this provides a

desirable way of providing the necessary hydrogen for reduction of the oxide.

A better understanding of the present invention may be had by considering the manner in which the device of FIG. 1 may be evacuated and bonded together. For purposes of a specific example, it will be assumed that the terminal members 14-18, inclusive, are of titanium and that the insulating members 10-13, inclusive, are fosterite ceramics having temperature coefficients of expansion which match reasonably well with those of titanium. Such a ceramic composition is described and claimed in copending application Serial No. 546,215, filed November 10, 1935, Alex. G. Pincus, now Patent No. 2,912,340, granted November 10, 1939 and assigned to the assignee of this application. The parts are assembled in the relationship shown in FIG. 1 and spring loaded, i.e. the parts are urged together in the stacked assembly shown in FIG. 1 by the application of spring pressure. Suitable shims of a metal which acts as a solder are interposed between adjacent surfaces of the insulating members 10-13 and terminal members 14-18, inclusive. Nickel is a suitable material for this shim. Also, inner walls of insulators 10 and 12 are coated with the constituents of the resistance film previously described. The assembly is placed within a bell jar and after a good vacuum in the order of $\frac{1}{10}$ micron, for example, is obtained, the assembly is brought to a temperature in the order of 1100° C. This latter temperature is sufficient to alloy the iron of the iron oxide and titanium and react it with a ceramic tube to provide a resistance film 25. This same temperature is also adequate to effect the formation of the resistance film on the inner wall of insulator 10 by reducing the oxide coating and reacting the titanium, the metal of the oxide and the ceramic. During this heating step also, the titanium-nickel alloys and bonds to the ceramic members to seal the device. The junctions between adjacent insulating and metal members form passages prior to the melting of the solder through which gases included within the envelope may escape to the vacuum system so that by a single heating step, the entire device is evacuated and bonded together.

While it is possible to process part of the device separately, for example, the subassembly including the metal terminals 14 and 15 and insulator 10 and resistance film 25, for example, could be formed by a separate heating step, it is an advantage of the present invention that the entire device, including both resistors, can be produced in a single operation.

In FIG. 2 the circuit relationship of the various elements is illustrated schematically. These elements have been designated by corresponding numerals in FIG. 1 but have been primed to designate the schematic showing. It is clear that the assembly of FIG. 1 provides the basic circuit combination including a triode electric discharge device, the grid-cathode resistor 24 and the anode-cathode resistor 25 all produced in a unitary device in a single assembly operation. The entire assembly is capable of operating at high temperatures, for example, temperatures exceeding 500° C.

It will be apparent to those skilled in the art that the concept involved in the present invention may be employed to the production of other circuit arrangements by means of a stacked assembly suitably chosen to produce the circuit elements desired. As one further example of a further embodiment of my invention, I have illustrated in FIG. 3 a pair of electric discharge devices arranged in axial alignment with the cathode ends of the devices in contiguous relationship. Since the discharge devices and resistor assemblies illustrated in FIG. 3 are substantially duplicates of the device shown in FIG. 1, the same reference numerals primed have been applied to corresponding parts of the upper discharge device while corresponding parts of the lower discharge device are designated by doubly primed reference numerals. It will be appreciated that the heater terminal 18 is not duplicated

and actually forms the element at which the two devices are made into a unitary aligned assembly. Also, the metal terminal members are of smaller diameter than the insulating spacers.

In addition to the elements of the stacked assembly, the remainder of the circuit connections required for the completion of a free-running multivibrator circuit are illustrated in FIG. 3 and this entire circuit is schematically shown in FIG. 4. The circuit elements corresponding to the upper and lower discharge devices are designated in FIG. 4 by numbers corresponding to those used in FIG. 3. As illustrated, the cathode terminals 17 are connected together and to ground as illustrated at 26. The terminals 14' and 14'' of the anode resistors are connected together by conductor 27 and to a source of positive direct voltage indicated as the B+ terminal. The anode terminal 15' of the upper discharge device is connected through a capacitor 28 to the grid or input terminal 16'' of the lower discharge device. In a similar manner, the anode terminal 15'' of the lower discharge device is connected with the control grid terminal 16' of the upper electric discharge device through a capacitor 29. The output of the multivibrator circuit may be taken from the anode terminal 15'' of the lower device through capacitor 30.

The operation of the free-running multivibrator circuit illustrated in FIG. 4 and embodied in the device as illustrated in FIG. 3 is not essential to the present invention, since it is a conventional type of circuit. It merely illustrates a type of system which may be produced with a stacked tube and component assembly with a minimum of external circuit connection and components. It will be appreciated, however, by those skilled in the art, that the conductivity of one of the two electric discharge devices increases as the conductivity of the other decreases and vice versa at a rate dependent upon the time constant of the circuits associated with the control grids.

From the foregoing detailed description of two embodiments of my invention, it will be apparent that the stacked assemblies provide a combination of an electric discharge device with one or more of the circuit resistors commonly employed with the devices, all in a structure which may be manufactured in a single assembly and exhaust operation and the resulting product of which is suitable for operation at high temperatures, for example, temperatures exceeding 500° C. and in environments which are subjected to radiation.

While I have described particular embodiments of my invention, it will be apparent to those skilled in the art that changes and modifications may be made without departing from my invention in its broader aspects and I aim, therefore, in the appended claims to cover all such changes and modifications as fall within the true spirit and scope of my invention.

What I claim as new and desire to secure by Letters Patent of the United States is:

1. An electric discharge device circuit assembly comprising a stack of disc-like metal terminal members and a plurality of hollow cylindrical insulating members disposed respectively between pairs of said terminal members and cooperating therewith to provide an envelope structure, electric discharge device electrodes within said envelope structure connected respectively with different ones of said terminals to provide a plurality of electric discharge devices each including an anode, a control member, and a cathode in spaced relation longitudinally of said stack and passive circuit elements within said envelope structure each electrically connected between a terminal to which one of said anodes is connected and a terminal spaced therefrom in said stack in the direction remote from the corresponding control member terminal to provide a plurality of electric discharge paths each having in series therewith one of said passive circuit elements and means coupling the anode-cathode circuit of one of said discharge devices to the control member of a second of said devices to control the discharge in the second of said dis-

charge devices in accordance with the discharge in the first of said devices.

2. An electric discharge device circuit assembly comprising a stack of disc-like metal terminal members and a plurality of hollow cylindrical insulating members disposed respectively between pairs of said terminal members and cooperating therewith to provide an envelope structure, electric discharge device electrodes within said envelope structure connected respectively with different ones of said terminals to provide a plurality of electric discharge devices each including an anode and a cathode in spaced relation longitudinally of said stack and passive circuit elements within said envelope structure each electrically connected between a terminal to which one of said anodes is connected and a terminal spaced therefrom in said stack in the direction remote from the corresponding cathode terminal to provide a plurality of electric discharge paths each having in series therewith one of said passive circuit elements and means coupling the anode-cathode circuit of one of said discharge devices to a terminal of a second of said discharge devices to control the discharge in the second of said discharge devices in accordance with the discharge in the first of said devices.

3. An electric discharge device circuit assembly comprising a stack of disc-like metal terminal members and a plurality of hollow cylindrical insulating members disposed respectively between pairs of said terminal members and cooperating therewith to provide an envelope structure electric discharge device electrodes within said envelope structure connected respectively with different ones of said terminals to provide a plurality of electric discharge devices each including an anode, a control member, and a cathode in spaced relation longitudinally of said stack and film resistor elements each on an inner wall of one of said insulating members and each electrically connected between a terminal to which one of said anodes is connected and a terminal spaced therefrom in said stack in the direction remote from the corresponding control member terminal to provide a plurality of electric discharge paths each having in series therewith
